FUEL BURNER INTERLOCKING SAFETY
CONTROL

Ira E. McCabe, Chicago, Ill.

Application December 3, 1949, Serial No. 130,896

15 Claims. (Cl. 158—28)

1

This invention relates to a new and improved electrical control apparatus and more particularly to apparatus of this character adapted to control the operation of liquid or gaseous fuel burners.

In a specific form it relates to a relay for the control of burner operating circuits, together with secondary circuits for control of the operation of said relay and mechanical interlocks, certain interlocks being electrically operated while others may require manual operation. More specifically, the apparatus includes a relay which is dependent upon a combustion responsive control device for maintenance of the relay in operation, other means being provided to initially bring the relay into operation and to maintain it in operation long enough for the combustion responsive device to be affected by combustion and to come into operation. Should combustion fail to take place within a predetermined period, the apparatus serves to shut off the burner circuit and the apparatus also serves to shut off said circuit if, at any time during operation, combustion ceases or is reduced to such an extent as to fail to operate the combustion responsive control device. A combustion responsive device suitable for operating with the present control apparatus, therefore, includes means responsive to an external switch, such for example as a room thermostat, to condition a combustion responsive element so that a burner circuit is closed to put a burner in operation. The device then includes means to take over the conditioning of the device and make it responsive to the existence of predetermined flame or combustion conditions so that the control apparatus may continue running of the burner as long as proper conditions prevail. A suitable combustion responsive device is shown in my co-pending application Serial No. 127,498, filed November 15, 1949, which comprises a switch, the movable contact of which is moved in response to the presence or absence of light emanating from the burner flame.

The present invention represents an improvement over such devices disclosed in my prior Patents Numbers 2,024,697 of December 17, 1935; 2,075,951 of April 6, 1937; and 2,158,515 of May 16, 1939. In the apparatus disclosed herein, a time of operation in responding to the absence of flame to shut down the burner and cut-off fuel either when attempting to establish the flame or maintain it, is so much faster that it may be advantageously used in connection with control of burners burning a high rate of fuel per hour. It thus becomes possible to use with such capacity

2

burners mechanical devices of the character herein disclosed which will assure positive protection against the delivery of large quantities of fuel without means to ignite it and to terminate such delivery quickly upon flame extinguishment from causes other than a normal shut down of the burner.

It is an object of the present invention to provide relay control apparatus which, when associated with a suitable combustion responsive device, will initiate burner operation and stop said burner operation upon failure of combustion to take place within a predetermined time.

It is a further object to provide such apparatus which will stop burner operation should combustion cease or be reduced below a predetermined level after it has been initiated.

It is an additional object to provide apparatus having a plurality of operating stages and means for progressively attaining said stages whereby the apparatus serves to initiate burner operation, provide a time delay to permit the operation to become effective and thereafter assume a stage of adjustment responsive to lack of illumination from flame of combustion or reduction of illumination intensity below a predetermined level.

It is a further object to provide apparatus which will return to its initial position upon cut-off of current supply and will automatically restore combustion upon resumption of current flow.

It is another object to provide apparatus of this character which will stop burner motor operation upon failure of ignition within a predetermined time and, also, upon interruption of flame propagation for a predetermined time and which requires manual reset to restore normal burner and control.

It is still another object to provide apparatus which will be dependent upon the proper functioning of a combustion responsive safety device in order to initiate and maintain operation of the burner in response to a demand for its operation with each initiation of a burner operation requiring the combustion device attaining its operative position indicative of no combustion and the maintenance of burner operation requiring the combustion device attaining its operative position indicative of the presence of combustion and, further, that no operation of the burner may occur if the circuits controlled by the combustion device are improperly made or short circuited.

Other and further objects will appear as the description proceeds.

I have shown certain preferred embodiments of

my invention in the accompanying drawings, in which—

Figure 1 is a front elevation showing the working parts of the control apparatus;

Figure 2 is a somewhat schematic wiring diagram of the apparatus and of the device controlled thereby;

Figure 3 is a horizontal section, partly broken away, taken on line 3—3 of Figure 1;

Figure 4 is a fragmentary view, on an enlarged scale, showing the parts of the control in the idle position;

Figure 5 is a view similar to Figure 4 showing the parts under normal running conditions;

Figure 6 shows the parts in the automatic cut-off position; and

Figure 7 is a fragmentary view showing a modified form of safety lock-out construction with the parts in operating position.

In order to better explain the operation of the control apparatus, reference will be made first to the general circuit layout shown in Figure 2. Here, the control apparatus is shown as mounted on a base 11 and comprising a closed transformer core 13 secured to the base and carrying the transformer primary coil 14 which is fixedly supported thereon. One side of this primary coil 14 is connected through a normally closed safety lock-out switch 130 to terminal 16, while the other side of the coil is connected to terminal 18. The terminals 16 and 18 are fed from regular power line alternating current of standard voltage, such as 115 volts, through the lines 20 and 21. This application discloses different structures as regards the lock-out safety feature of the invention. One form, strictly mechanical, is described with respect to its representation in Figure 6. In this form the safety switch 130 may be omitted and the two sides of the primary coil 14 connected directly to terminals 16 and 18. The other form including switch 130 is described in connection with a detailed showing of the switch operating structure in Figure 7.

Power line 20 passes through a boiler limit control 23. It will be understood that this boiler limit control comprises a normally closed switch which, however, may be opened by abnormal boiler conditions, such as excess pressure or excess temperature. Such controls are well known and its specific construction forms no part of the present invention.

The tiltable mercury switch 25 is carried on one end of the rockable carrier 26, the latter being pivoted at 27 on the transformer core 13. This mercury switch 25 is shown in Figure 2 in its open position, the two contact members of the switch being connected to the terminals 16 and 29 respectively. The terminal 30 is directly connected to the incoming line terminal 18. Wires 32 and 34 lead from the terminals 29 and 30 to the burner motor 36. The ignition transformer 38 is connected in parallel with the burner motor 36 by the wires 39 and 40. The ignition gap is shown at 42 with the grounded electrode 43. As thus shown, ignition is constantly provided as long as the burner motor is energized. When it may be desired to cut off ignition a predetermined period after initiating burner operation, any desired form of ignition cut-off means may be interposed in the ignition circuit to accomplish this. One such form may be that disclosed in my prior Patent No. 2,287,386 of June 23, 1942.

The secondary coil 45 on the transformer core 13 is supported by the rocking carrier 26 on the opposite side of the pivot 27 from the mercury

switch 25. One side of the secondary 45 is connected to terminal 47, with the other side being connected to terminal 48. The light responsive switch 50 includes a fixed contact 51 which is connected by wire 52 to terminal 68. The switch 50 includes movable switch member 56 which is externally connected to wire 51 leading to terminal 48. It will be noted that, in the specific forms of construction shown, the fixed terminal 51 terminates in contact with a globule of mercury 59, a portion of the mercury being drawn up in the capillary tube 60. The mercury in the tube 60 is exposed through an opening 61 for engagement by the movable contact 56. This movable contact is moved by expansion of the expandable member 63. This member is expandable by the application of heat, either directly or as heat derived from the concentration of light rays of the flame upon the member 63. The member 63, being dark and opaque, absorbs the light rays and the light energy is converted into a form of heat energy.

The heating coil 65 is connected at one end to the wire 57, this being the same wire to which the moving contact 56 is connected. The other end of the heating coil 65 is connected by wire 67 to terminal 54. The room thermostat 70 is connected by wire 71 to terminal 68 and by wire 73 to terminal 47. The solenoid coil 76 is connected by wire 77 to terminal 54 and by wire 79 to terminal 68. This solenoid 76 is provided with a fixed iron core 80.

The particular construction of the light and heat responsive switch 50 forms no part of the present invention, this being covered by my co-pending application Serial No. 127,498, filed November 15, 1949. The thermostatic switch 70, also, forms no part of the present invention. This may be any standard type of heat responsive thermostat located in a room or other space being heated by the apparatus which the present device serves to control.

It will be apparent from an examination of the circuit diagram that, assuming the given boiler conditions are normal and the boiler limit control 23 is in normal position with closed contacts, then the established line voltage is continuously applied through wires 20 and 21 and terminals 16 and 18 to the primary 14 of the transformer. This transformer is of the relay type with the secondary 45 pivotally mounted on the rocking carrier 26, as has been described. When the transformer secondary 45 is included in a closed circuit of such character that it draws a substantial amount of current, the magnetic repulsion is such that the secondary 45 is thrust away from the primary 14. This causes the carrier 26 to rock in the counterclockwise direction about its pivot 27 which tilts the mercury switch 25 to such a position that the mercury therein closes the circuit through the switch. It will be apparent that, when the circuit is closed through the switch 25, line current is supplied through the switch both to the burner motor 36 and the ignition coil 38.

However, this action only takes place when a closed circuit is provided including the secondary 45, the circuit drawing sufficient current to cause the necessary magnetic repulsion. It will be apparent that the circuit through secondary 45 may be closed through terminal 48, wire 57, movable switch contact 56, fixed switch contact 51, wire 52, terminal 68, wire 71, thermostat 70, wire 73 and back through the terminal 47 to the other side 75 of the secondary. It will be noted, however, that

under normal conditions, with the motor off and fire out, the switch 50 is open so that the circuit will not be closed as described. An alternate circuit extends from the secondary 45 through terminal 48, line 57, heating resistance 65, line 67, terminal 54, line 77, solenoid 76, line 79, terminal 68, line 71, room thermostat 70 and line 73 back to terminal 47. In this case, both the heating coil 65 and solenoid coil 76 are connected in series with the secondary 45. It will be further noted, however, that the circuit does not become closed until the room thermostat 70 becomes closed under the temperature conditions for which that thermostat is adjusted.

When the alternate circuit is closed by the room thermostat, current flows through the transformer secondary circuit but, with the heating coil 65 and/or solenoid 76 being included therein, sufficient resistance is interposed in the circuit to reduce the current flow so that repulsion of the secondary coil does not occur. However, the heating coil is energized and it will be apparent that the heating coil 65, being in close proximity to the expandable member 63, will heat that member to such an extent as to swing the moving contact 56 into engagement with the mercury at 61 and establish a circuit through the mercury pool at 59 through fixed contact 51 and back through line 52 to the terminal 68. Thus, as previously described, the secondary circuit across terminals 47-48, including the relay secondary 45 and thermostat 70, is completed and, as a result, the alternate circuit, including the heating coil 65 and solenoid 76, is shunted whereupon magnetic repulsion of the secondary coil occurs to close the mercury switch 25. Upon initiating burner operation, the establishment of flame provides a source of light from which the switch 50 derives heat to maintain the expandable member 63 in heated condition, which heat replaces that cut off when the heating coil 65 is shunted. The member 63 is adapted to be exposed to the light radiating from the burner flame and, being dark and opaque, light rays are absorbed and the light energy converted into heat. The expandable member 63 is heated sufficiently by the heating coil 65, when effecting a closure of the switch contact, that opening of the switch contact upon de-energization of the coil will not take place before a predetermined lapse of time which is of such duration that, normally, establishment of combustion and heating of member 63 by radiant energy will occur to maintain the contact in closed position. Therefore, with the normal establishment of combustion, the switch 50 remains closed after de-energization of the heating coil 65 and will remain closed for continued operation of the burner as long as the demand for same is made and the burner flame exists.

The motor circuit must, however, be opened if a flame fails to appear to actuate the switch 50 after the lapse of time provided for establishment of combustion occurs. This control is adapted for use in connection with burners using substantial quantities of oil per minute and, if the burner is operating but the liquid fuel is not ignited, there will be not only substantial losses of fuel, but fuel will flow into the combustion chamber in quantities which can become very dangerous. It is important, therefore, that the control be so designed that it not only terminates operation of the motor 36 and, consequently, flow of fuel when the flame is extinguished for any reason but, also, must promptly take the same action if the fuel

fails to ignite and produce a flame in a comparatively short time after the motor is put in operation.

The apparatus is designed to take care of these several contingencies and the various interlocks of the mechanical means controlling the movement of the rocking carrier 26 and, consequently, the motor circuit controlled by the mercury switch 25 are shown in Figure 1 in normal inactive view and are shown on an enlarged scale in Figures 3 to 6 inclusive.

Referring first to Figure 4 showing the parts in the idle position, that is, with the burner motor off, the relay release catch 85 is mounted to swing freely on the pivot 86, being held in position on the pivot by the U-ring 87. The release catch 85 is so weighted relative to its pivot 86 that it would be normally positioned by gravity in a position swung slightly counter-clockwise from that in which it is shown in Figure 4 were it not for the interposition of the stop arm 93. The relay release lever 90 is pivoted on the fixed pin 91, this relay release having the transversely extending stop arm 93, one edge of which is adapted to engage the shoulder 94 formed on the lower portion of the relay release catch 85. In other positions of the parts, this stop arm 93 passes above the ledge 95 which is located immediately above the shoulder 94.

The relay release catch 85 is provided with a contact finger 97 which, in certain positions of the parts, engages the lower transversely extending abutment portion 99 of the safety latch carrier 101. The relay release 90 is further provided with an upwardly extending portion 103, upon the forward face of which is secured a small iron section 105 adapted to be attracted by the core 80 of the solenoid 76 when that solenoid is energized. The safety latch carrier 101 is shown as pivoted on the pivot member 27 to which is pivoted the carrier 26 carrying the transformer secondary 45. This safety latch carrier 101, however, is movable on the pivot entirely independent of movement of the carrier 26 which supports the secondary 45, but is weighted to the right of its pivot so as to assume a position by gravity normally resulting in its movement as a unit with the secondary coil 45. This safety latch carrier 101 has an inturned portion at 107 to which is connected an arm 108 extending parallel with the main portion of the safety latch carrier 101. An iron section 109 is secured to the arm 108 so that, when placed in the proximity of core 80 of solenoid 76, it may be attracted by the core when the solenoid is energized.

The safety latch 111 is pivoted at 112 upon the safety latch carrier 101. This safety latch has an operating arm 113 which may be engaged manually or by any desired operating means, not shown, for swinging the safety latch 111 in the counterclockwise direction about its pivot 112. A safety catch 115 is secured to the relay secondary construction by the screw 116. This catch 115, therefore, moves with the secondary 45 and independently of the latch 111. The safety latch 111 is provided with a notch 118 adapted, under certain conditions, to engage the left side of the safety catch 115, as shown, for example, in Figure 6.

The repulsion of the secondary 45 normally causes movement of the latch carrier 101, which is moved by and with the secondary since the upper corner 121 of the secondary carrier assembly engages the transversely extending portion 107 of the safety latch carrier, which car-

rier is weighted to the right of the pivot 27 whereby it assumes, by gravity, its position in abutment with corner 121. The safety latch 111 carried by the safety latch carrier 101 normally rests upon the safety catch 115, as shown in Figures 1 and 4, so that this latch 111 moves with the carrier 101 as a unit with the secondary coil 45 as it swings about its pivot 27.

The apparatus is shown in its normal or non-operating position in Figure 4 of the drawings, in which case the secondary 45 is swung downwardly immediately adjacent the primary. The parts are also shown in this position in Figure 1. In this position, the relay release lever 90 has its stop arm 93 in abutment with portion 99 of the safety latch carrier 101 in substantially direct alignment with the relay release lever pivot 91 so that, with the parts in this position, the stop arm 93 prevents the secondary 45 from being swung upwardly and, as a consequence, prevents the mercury switch 25 from being swung to the operative or closed position.

When the initial circuit is closed by means of room thermostat 70, the electromagnet 76 is energized and attracts the magnetic section 105 carried by the relay release member 90, thus lifting the stop portion 93 of the relay release lever 90 so that it clears the shoulder 94 and also clears the abutting portion 99 of the safety latch carrier 101.

When the flame switch 50 becomes operative and closes to establish the running circuit, the secondary 45 is repelled and assumes the position shown in Figure 5. This flame switch 50 is initially operated by heat derived from the resistance coil 65 which, as has been previously described, is placed in the circuit at the same time as the solenoid 76 of the electromagnet. It is to be understood that the manner of operation of the flame switch 50 is such that light rays from the flame focused upon the temperature responsive element 63 will maintain the element heated and maintain the switch circuit closed after the heating coil 65 is de-energized. De-energization of the heating coil 65, as well as the solenoid 76, occurs with the closure of the switch 50, as previously described.

Relay devices of the character and for the purposes herein disclosed are intended to operate to provide a closure of the relay switch, that is, the mercury switch 25, at a voltage not less than 15% below the rated voltage of the relay. At the lower portion of its operating range, the repulsion of the relay secondary is not as forceful as under the higher voltage conditions prevailing at the upper portions of its operating range. Since the magnet 76 is de-energized at the time of the repulsion of the secondary 45, it would not be desirable for the relay release 90, with its stop member 93, which release is no longer held by magnet 76, to fall back to block the repulsion of the secondary 45 when the movement of this secondary is slow due to low voltage conditions. If such a low voltage condition exists, the relay release catch 85 prevents the dropping of the relay release stop portion 93 to a blocking position upon de-magnetization since the portion 93 rests on the ledge 95 of the catch 85. As has been stated, the catch 85 is so balanced that gravity causes it to swing under the relay release portion 93 when that portion is lifted above the shoulder 94. This permits the secondary to continue to move to its repelled position, whereupon the relay release catch 85 is swung to the left or in the clockwise direction about its pivot 86 by

contact of the lower finger 97 with the abutment portion 99 of the safety latch carrier 101, as shown in Figure 5.

Figure 5 shows the position of the parts under normal running conditions. Here, the secondary coil 45, safety latch 111 and the safety latch carrier 101 have moved upward as a unit and the burner switch 25 is closed. During this movement, the abutment 99 of the carrier 101 has engaged the lower end 97 of the relay release catch 85 to release the relay release member 90 which, being no longer held by the magnet 76, drops back to its idle position. In this position, the stop portion 93 is in a slot 122 formed in the latch carrier 101 above the abutment portion 99.

It is to be noted here that should a current interruption of a momentary nature take place in either the primary 14 or the secondary 45, resulting in the de-energization of the secondary, it will fall back to its position, as shown in Figures 1 and 4, and this will restore the relay release latch 90 and its portion 93 to the position shown in Figure 4, preventing repulsion of the secondary coil 45 even though current be restored to the primary and secondary after its interruption. What is now required to restore operation of the control apparatus is an opening of the circuit passing through the flame switch 50 which, in the form of construction disclosed, occurs in about five seconds, provided the heater 65 therein is not contributing any heat. In case the heater 65 has been in circuit, the time may approach a maximum of fifteen seconds. With the opening of the contact 56 of the flame switch 50, the circuit, including the electromagnet 76, is restored, the relay release 93 freeing the safety latch carrier 101 and permitting the device to again reach the running position of Figure 5, as has been previously described.

Figure 6 illustrates the parts in the position assumed when through failure of ignition of the burner, no flame has been established to maintain the heating of the actuator or expandable member 63 of the flame switch 50, which heating is required to maintain the contact 56 closed after de-energization of the heating coil 65. The parts will take the same position when, after the flame has been ignited, it goes out and there is a cessation of heat emanating from the light rays of the flame. With regard to the operation upon ignition failure, attention is invited first to the parts as shown in Figures 2 and 5. It is to be noted that when the heater 65 of the flame switch causes closure of the contact 56 therein to complete the running circuit, the repulsion of the secondary 45 which takes place places the upper left extremity 109 of the safety latch carrier 101 in the magnetic field zone of the magnet. At this time, however, by virtue of the fact that the running circuit is energized, the magnet 76 is de-energized. The burner switch being closed, combustion and establishment of a flame for maintaining the flame switch 50 closed should take place. If this does not take place, flame switch 50 will open circuit, thus restoring the initial control circuit, which includes the electromagnet 76 and the flame switch heater 65. Two different actions now take place. First, energization of the magnet 76 causes it to attract and hold the magnetic section 109 of the safety latch carrier 101 which holds that carrier in the position it had assumed upon closing of the flame switch 50 by the heater 65 therein. Second, the establishment of the preliminary control circuit when the flame switch 50 opened restored the

resistance of the magnet coil 76 and the switch heater 65 into the circuit of the secondary coil 45, which results in reducing the value of the current passing through the secondary below that required to maintain the secondary repelled from the primary and in its upper position, as shown in Figure 5. The secondary 45 thus falls and the parts assume the position in which they are shown in Figure 6. Thus, in Figure 6, the magnetic portion 109 of the safety latch carrier 101 is in contact with the core 80 of the magnet 76, holding the carrier 101 in its upper position while, on the other hand, the secondary 45 has fallen to its lower position where it rests on the primary 14.

The safety latch 111 carried by the carrier 101, which latter is held by the magnet 76, also assumes a position swung to the left, as viewed in Figure 6, so that the safety catch notch 118 has passed over the safety catch 115. With the parts in this position, as the heater 65 in the flame switch 50 is caused to heat and to close the switch 56, the expected repulsion of the secondary coil 45 to close the mercury switch 25 does not take place because the relay safety catch 115 engages the notch 118 and its upward movement is arrested. As long as the circuit of the room thermostat 10 remains closed, there will occur a continuous opening and closing of the contact 55 of the flame switch 50 by virtue of the alternate energization of the preliminary circuit and the running circuit through the heating and cooling of the expandable element 63 of the flame switch 50, but without resulting in the closing of the mercury switch 25.

The safety latch 111 is provided, however, at its left end with the extension piece of actuating member 113 which is adapted to be engaged by any suitable means, not shown, whereby the lower portion of the extension 113 may be pushed laterally to the right to swing the safety latch 111 around its pivot 112 in the counter-clockwise direction. This movement will free the notch 118 of the safety latch from the latch member 115 and permit a subsequent repulsion of the secondary coil to take place so that the parts will return to the position shown in Figure 5.

This will again close the circuit through the motor switch 25 and put the burner into operation. Should the burner again fail to ignite, the previously described action will take place and the secondary will again drop down, the latch 115 again engaging the notch 118.

The form of construction shown in Figure 7 is generally similar in construction to that shown in Figure 6 but is provided with a different form of latch and a normally closed mercury switch 130 connected in the primary circuit as shown in Figure 2 or, if desired, interposed in the burner motor circuit. This switch 130 and its associated structure accomplishes the same result of shutting down the burner after ignition failure until corrective measures have been taken to assure ignition and the control reset as the structure of Figure 6. Whereas ignition failure with the structure of Figure 6 results in the mechanical lock-out of the burner switch 25, the modification shown in Figure 7 accomplishes the same result by opening the normally closed mercury switch 130. The apparatus includes the electromagnet having the solenoid coil 76 and core 80. The secondary coil 45 is supported on the carrier 26 pivoted on pin 27. A mercury switch 130 is carried by the bell crank lever 132 which is pivoted on the pin 134. The bell crank 75

132 has a long arm 135 carrying a roller 137 near its upper end, the arm and roller being of such weight that with their long lever arm they tend, by gravity, to swing the bell crank lever 132 in the clockwise direction about the pivot pin 134. The lever 132 and switch 130 are shown in Figure 7 in the closed circuit position.

A roller engaging member 138 is pivoted on pin 27 in the same manner as the latch carrier 101 of the other form of construction, and moves in the counter-clockwise direction with repulsion of the secondary 45. The member 138 has an upwardly extending arm 140 which has an upper arcuate surface 142 upon which the roller 137 may rest. The member 138 also has a forwardly extending arm 144 carrying an iron section 145 adapted to be attracted by the magnetized core 80 of the electromagnet. The fixed track member 147 is carried by the secondary 45 and always moves therewith. This member 147 has an upper arcuate surface 149 which, as shown in Figure 7, serves as a continuation of the arcuate surface 142 of member 138.

In the operation of this form of construction, 25 when the flame goes out or there is failure of initial ignition, and the first control circuit is again closed as described in connection with the form of construction shown in Figures 1 to 6, the solenoid 76 is energized and core 80 attracts and holds magnetic member 145, thus holding the member 138 in the position shown in broken lines in Figure 7. At this time, the current flow through the secondary 45 is inadequate to maintain it repelled from the primary and the 30 secondary returns to the full line position of Figure 7 carrying with it the fixed track member 147, upon the upper arcuate surface of which the roller 137 has been resting. This roller then drops down between the rear of the upwardly 35 extending arm 140 of the member 138 and the front of the member 147. This movement is caused by gravity and the switch 130 is swung upwardly and opens the circuit. The switch 130 is normally connected in the main circuit to the transformer primary and, when open, cuts off all current to the apparatus. To resume operation again, the switch is reset by manually rotating the bell crank 132, carrying the switch 130, in the counter-clockwise direction to restore it to the position shown in Figure 7. When the bell crank is so rotated, the member 138 will drop back by gravity as the electromagnet is no longer energized and all parts will be restored to the full line position of Figure 7 with the pin 137 resting on the arcuate surface 142.

55 The repulsion relay, as shown in the drawings and described, is arranged to operate on alternating current with low voltage current being induced in the secondary when the relay is energized. It is to be understood, however, that the relay may be adapted to direct current applications by properly connecting the pair of coils together so that one is repelled from the other when both are energized.

60 The invention, as disclosed herein, comprises a controlling device for liquid or gaseous fuel burners meeting the aforementioned objectives in a manner which renders its operation dependent upon proper functioning of a combustion device, which latter device is responsive to normal combustion conditions to permit burner operation and responsive to abnormal combustion conditions, or, failure to attain combustion, to prevent burner operation. With the combustion responsive device acting as a safeguard

against burner operation under abnormal conditions, the present invention provides that combustion be attained and continued thereafter through the process if a particular sequence of control operation and only of the combustion responsive device, upon which sequence of operation is made dependent, is operative to perform its safeguarding functions against the establishment of hazardous conditions. Each recurring operation of the burner, after a shutdown, must await the return of the combustion responsive device to its normal starting position and the operation of the burner, upon the proper functioning of the combustion responsive device upon initiating and establishing combustion.

While certain preferred embodiments of the invention have been shown, they are to be understood to be illustrative only as it is capable of further variation to meet differing conditions and requirements, and I contemplate such modifications as come within the spirit and scope of the appended claims. Also, the apparatus may be used with other devices than the flame switch disclosed in my co-pending application to which reference has been made. Other forms of electrothermal actuators may be used in the initiating circuit to close the switch establishing the running circuit and other forms of combustion responsive switches may be used to parallel the electrothermally actuated switch to maintain the running circuit, permitting the electro-thermal actuator to cool and open its switch.

I claim:

1. Fuel burner control apparatus comprising a relay having actuating means for closing connections to a burner circuit, means for energizing said relay to operate said actuating means, an initiating circuit including said relay energizing means, resistance of such value as to prevent passage of sufficient current to operate the relay and an electromagnet; a low resistance shunt relay operating circuit, mechanical means for blocking the actuating means, said means being movable to unblocking position by attraction of said electromagnet upon energization of the initiating circuit, and means responsive to energization of the initiating circuit to effect closure of the shunt circuit reducing the resistance and permitting operation of the unblocked relay and responsive to combustion to maintain the shunt circuit closed while combustion continues.

2. Fuel burner control apparatus comprising a relay having actuating means for closing connections to a burner circuit, means for energizing said relay to operate said actuating means, an initiating circuit including said relay energizing means, resistance of such value as to prevent passage of sufficient current to operate the relay and an electromagnet; a low resistance shunt relay operating circuit, mechanical means for blocking the actuating means, said means being movable to unblocking position by attraction of said electromagnet upon energization of the initiating circuit, means responsive to energization of the initiating circuit to effect closure of the shunt circuit reducing the resistance and permitting operation of the unblocked relay and responsive to combustion to maintain the shunt circuit closed while combustion continues, and a latch for blocking further operation of the actuating means, said latch being rendered operative by attraction of said electromagnet upon restoring the initiating circuit following combustion failure.

3. Fuel burner control apparatus comprising a relay having actuating means for closing connections to a burner circuit, means for energizing said relay to operate said actuating means, an initiating circuit including said relay energizing means, resistance of such value as to prevent passage of sufficient current to operate the relay and an electromagnet; a low resistance shunt relay operating circuit, mechanical means for blocking the actuating means, said means being movable to unblocking position by attraction of said electromagnet upon energization of the initiating circuit, means responsive to energization of the initiating circuit to effect closure of the shunt circuit reducing the resistance and permitting operation of the unblocked relay and responsive to combustion to maintain the shunt circuit closed while combustion continues and upon combustion failure to open the shunt circuit and restore the initiating circuit, a normally closed switch controlling the burner circuit, and means responsive upon restoring the initiating circuit and subsequent operation of the relay to open the burner circuit, to open the normally closed switch.
4. Fuel burner control apparatus comprising a repulsion type relay, connections for closing a burner circuit upon actuation of the relay, mechanical means normally blocking repulsion of the relay secondary, an initiating circuit including the relay secondary, resistance of such value as to prevent passage of repulsion current through the secondary and electrical means for unblocking the secondary; a low resistance shunt relay operating circuit including the relay secondary, the initiating circuit when energized operating the means for unblocking the secondary, and means responsive to energization of the initiating circuit to effect a closure of the shunt circuit reducing the resistance and permitting repulsion of the secondary and responsive to combustion conditions to maintain the shunt circuit closed while combustion continues.
5. Fuel burner control apparatus comprising a repulsion type relay, connections for closing a burner circuit upon actuation of the relay, mechanical means normally blocking repulsion movement of the relay secondary, an initiating circuit including the relay secondary, resistances of such value as to prevent passage of repulsion current through the secondary and electrical means for unblocking the secondary; a low resistance shunt relay operating circuit including the relay secondary, said initiating circuit when energized operating the means unblocking the secondary, means for maintaining the secondary unblocked until said secondary has been moved to operating position, and means responsive to the energization of the initiating circuit to effect closure of the shunt circuit reducing the resistance and permitting repulsion of the unblocked secondary and responsive to combustion conditions to maintain the shunt circuit closed while combustion continues.
6. Fuel burner control apparatus comprising a repulsion type relay, connections for closing a burner circuit upon actuation of the relay, an initiating circuit including the relay secondary, resistances of such value as to prevent passage of repulsion current through said secondary, and an electromagnet; a low resistance shunt relay operating circuit including the relay secondary, mechanical means for blocking repulsion of the secondary, said means being movable to unblocking position by attraction of said electromagnet.

upon energization of the initiating circuit, and means responsive to the energization of the initiating circuit to effect closure of the shunt circuit reducing the resistance, said last named means permitting repulsion of the unblocked secondary and being responsive to combustion conditions to maintain the shunt circuit closed while combustion continues.

7. Fuel burner control apparatus comprising a repulsion type relay, connections for closing a burner circuit upon actuation of the relay, an initiating circuit including the relay secondary, resistances of such value as to prevent passage of repulsion current through said secondary and an electro-magnet; a low resistance shunt relay operating circuit including the relay secondary, mechanical means for blocking repulsion of the secondary, said means being movable to unblocking position by attraction of said electromagnet upon energization of the initiating circuit, means responsive to the energization of the initiating circuit to effect closure of the shunt circuit reducing the resistance and permitting repulsion of the unblocked secondary, and responsive to combustion conditions to maintain the shunt circuit closed while combustion continues and upon combustion failure to open the shunt circuit and restore the initiating circuit, and a latch for blocking further repulsion of the secondary, said latch being rendered operative by attraction of said electromagnet upon restoring the initiating circuit following combustion failure.

8. Fuel burner control apparatus comprising a repulsion type relay, connections for closing a burner circuit upon actuation of the relay, a pivoted carrier for the relay secondary, a burner circuit switch operable by movement of the carrier, an electromagnet adjacent the secondary, a relay release lever pivoted adjacent the relay secondary, said release lever having a magnetic member in operative relationship with the electromagnet and having a portion normally blocking movement of the relay secondary, attraction by the electromagnet serving to move the blocking portion to unblocking position to permit operation of the relay to close the burner circuit switch, and a pivoted release lever catch adapted to engage and hold the release lever when said lever is moved to unblocking position, said catch being movable to become disengaged from said release lever upon repulsion of the relay secondary.

9. Fuel burner control apparatus comprising a repulsion type relay, connections for closing a burner circuit upon actuation of the relay, a pivoted carrier for the relay secondary, a burner circuit switch operable by movement of the carrier, an electromagnet adjacent the secondary, a relay release lever pivoted adjacent the relay secondary, said release lever having a magnetic member in operative relationship with the electromagnet and having a portion normally blocking movement of the relay secondary, attraction by the electromagnet serving to move the blocking portion to unblocking position to permit operation of the relay to close the burner circuit switch, safety latch mechanism carried by the pivoted carrier, said mechanism including a magnetic member moved to operative relationship with the electromagnet upon operation of the relay to close the switch, said safety latch being put in operation by the electromagnet and the subsequent actuation of the relay to inoperative posi-

tion to block thereafter further operation of the relay to close the switch.

10. Fuel burner control apparatus comprising a repulsion type relay having a fixed coil and a movable coil, connections for closing a burner circuit upon repulsion of the movable coil, an initiating circuit including the movable coil, resistances of such value as to prevent passage of the repulsion current through the movable coil and an electromagnet; a low resistance shunt operating circuit including the movable coil, mechanical means for blocking repulsion of the movable coil, said means being movable to unblocking position by attraction of said electromagnet upon energization of the initiating circuit, means responsive to the energization of the initiating circuit to effect closure of the shunt circuit reducing the resistance and permitting repulsion of the unblocked movable coil, and responsive to combustion conditions to maintain the shunt circuit closed while combustion continues and upon combustion failure to open the shunt circuit and restore the initiating circuit, and means responsive upon restoring the initiating circuit and subsequent movement of the movable coil to open the burner circuit to prevent further closure of the burner circuit.

11. Fuel burner control apparatus comprising a repulsion type relay having a fixed coil and a movable coil, an initiating circuit including the movable coil, resistances of such value as to prevent passage of repulsion current through the movable coil and an electromagnet; a low resistance shunt operating circuit including the movable coil, mechanical means for blocking repulsion of the movable coil, said means being movable to unblocking position by attraction of said electromagnet upon energization of the initiating circuit, means responsive to the energization of the initiating circuit to effect closure of the shunt circuit reducing the resistance and permitting repulsion of the unblocked movable coil, and responsive to combustion conditions to maintain the shunt circuit closed while combustion continues and upon combustion failure to open the shunt circuit and restore the initiating circuit, connections for closing a burner circuit upon repulsion of the movable coil, a normally closed switch controlling the burner circuit, and means responsive upon restoring the initiating circuit and subsequent movement of the movable coil to open the burner circuit to open the normally closed switch.

12. Fuel burner control apparatus comprising a relay having actuating means for closing connections to a burner circuit, means for energizing said relay to operate said actuating means, an initiating circuit including said relay energizing means, resistance of such value as to prevent passage of sufficient current to operate the relay and an electromagnet; a low resistance shunt relay operating circuit, mechanical means for blocking the actuating means, said means being movable to unblocking position by attraction of said electromagnet upon energization of the initiating circuit, means responsive to the energization of the initiating circuit to effect closure of the shunt circuit reducing the resistance and permitting operation of the unblocked relay and responsive to combustion to maintain the shunt circuit closed while combustion continues and upon combustion failure to open the shunt circuit and restore the initiating circuit, and means responsive upon restoring the initiating circuit and subsequent operation of the relay to open the

burner circuit to prevent further closure of the burner circuit.

13. Fuel burner control apparatus comprising a relay having actuating means for closing connections to a burner circuit upon actuation of the relay, mechanical means normally blocking operation of the relay actuating means to prevent closure of the burner connections, electrical means for moving the mechanical means to unblocking position, an initiating circuit including the relay actuating means, resistance of such value as to prevent passage of sufficient current to operate the relay actuating means, and the electrical means for moving the mechanical means to unblocking position, the initiating circuit when energized operating the said electrical means and moving the mechanical means to unblocking position, a low resistance shunt relay operating circuit including the relay actuating means, means responsive to energization of the initiating circuit to effect a closure of the shunt circuit and operation of the relay actuating means and responsive to combustion conditions to maintain the shunt circuit closed while combustion continues.

14. Fuel burner control apparatus comprising a relay having actuating means for closing connections to a burner circuit upon actuation of the relay, mechanical means normally blocking operation of the relay actuating means to prevent closure of the burner connections, electrical means for moving the mechanical means to unblocking position, an initiating circuit including the relay actuating means, resistance of such value as to prevent passage of sufficient current to operate the relay actuating means, and the electrical means for moving the mechanical means to unblocking position, the initiating circuit when energized operating the said electrical means and moving the mechanical means to unblocking position, a low resistance shunt relay operating circuit including the relay actuating means, means responsive to energization of the initiating circuit to effect a closure of the shunt circuit and operation of the relay actuating means, and responsive to combustion conditions to maintain the shunt circuit closed while combustion continues, said last named means including a switch for closing the relay operating circuit, said switch being heat responsive and being in heating relationship to resistance in the initiating circuit whereby the relay operating

circuit is closed a predetermined time after the initiating circuit is closed.

15. Fuel burner control apparatus comprising a relay having actuating means for closing connections to a burner circuit upon actuation of the relay, mechanical means normally blocking operation of the relay actuating means to prevent closure of the burner connections, electrical means for moving the mechanical means to unblocking position, an initiating circuit including the relay actuating means, resistance of such value as to prevent passage of sufficient current to operate the relay actuating means, and the electrical means for moving the mechanical means to unblocking position, the initiating circuit when energized operating the said electrical means and moving the mechanical means to unblocking position, a low resistance shunt relay operating circuit including the relay actuating means, means responsive to energization of the initiating circuit to effect a closure of the shunt circuit and operation of the relay actuating means, and responsive to combustion conditions to maintain the shunt circuit closed while combustion continues, said last named means including a switch for closing the relay operating circuit, said switch being heat responsive and being in heating relationship to resistance in the initiating circuit whereby the relay operating circuit is closed a predetermined time after the initiating circuit is closed, and a latch for blocking further operation of the relay actuating means, said latch being rendered operative by the electrical means for moving the mechanical blocking means upon restoring the initiating circuit upon combustion failure.
